G. W. BROWN,
AUTOMATICALLY OPERATED GATE AND DOOR.
APPLICATION FILED APR. 9, 1921.

1,390,015.

Patented Sept. 6, 1921.

2 SHEETS—SHEET 2.

UNITED STATES PATENT OFFICE.

GEORGE W. BROWN, OF FORT WORTH, TEXAS, ASSIGNOR OF ONE-FOURTH TO H. M. COLEMAN, OF INDIANAPOLIS, INDIANA.

AUTOMATICALLY-OPERATED GATE AND DOOR.

1,390,015.

Specification of Letters Patent. Patented Sept. 6, 1921.

Application filed April 9, 1921. Serial No. 459,950.

To all whom it may concern:

Be it known that I, GEORGE W. BROWN, a citizen of the United States of America, residing at Fort Worth, in the county of 5 Tarrant and State of Texas, have invented certain new and useful Improvements in Automatically-Operated Gates and Doors, of which the following is a specification.

My invention relates to automatically operated gates and doors; and the object is to provide double gates or doors which will be automatically opened and closed by a moving vehicle and without the attention of a person to open or close the gates or 15 doors. One advantage is in the use of automobiles and garages, a person can drive in the garage without having to get out in the rain, if it should be raining, and he can also get in the automobile while standing in the 20 garage and back out. The doors will open automatically on the approach of the vehicle and automatically close when the vehicle leaves the doors. This is true also of 25 gates on farms, ranches, and other places. Other objects and advantages will be fully explained in the following description and the invention will be more particularly pointed out in the claims.

Reference is had to the accompanying 30 drawings which form a part of this application.

Figure 1 is a perspective view of the improvement applied to gates. Fig. 2 is a front view of a garage, showing the doors 35 swung open and showing the track down and showing one door in dotted outline in closed position. Fig. 3 is a vertical longitudinal section of one track approach and showing a door gate in open position and 40 showing the other track approach broken away. Fig. 4 is an enlarged detailed view of one of the throw levers and coöperating parts. Fig. 5 is a horizontal section of one of the uprights showing the provision for 45 adjustment of the fulcrum bolt.

Similar characters of reference are used to indicate the same parts throughout the several views.

On each side of the gate a frame is 50 provided consisting of two uprights 1 and 2 which are suitably connected at the bottom and braced by a block or sill 3. The only other connection of the uprights 1 and 2 to each other is by means of the fulcrum 55 bolt 4 on which the door or gate swings.

For out-door gates or closures, two gate members 5 and 6 are provided and these members are pivotally mounted on the bolts 4. The doors 5 and 6 are operatively connected to a depressible supporting beam 7 60 which extends entirely across the drive way. This depressible beam 7 is supported on the fulcrum bolts 4 in the normal inoperative position when the doors are closed. Curved operating levers 8 are attached rigidly to the lower cross-bars 9 of the gates or doors, these cross-bars projecting between the uprights 1 and 2 when the doors are closed, as in Fig. 1 and standing vertically between these uprights when the doors are open, as 70 in Fig. 2. A clevis 10 is pivotally connected to each end of the beam 7 and provided with a threaded shank 11. A link bar 12 is hung on the curved operating lever 8 and provided with a threaded shank 13. A turn-buckle 14 adjustably connects the shanks 13 and 11 and by such means the throw of the doors or gates is regulated. The link bars 12 are hung on the levers 8 and provided with roller bearings 15 so that the link 80 bars will readily depress the levers for raising the doors or gates when the depressible beam 7 is forced downwardly by an approaching vehicle.

The approaches or drive ways 16 are 85 fulcrumed on supporting beams 17 and against abutments 18. The beams 17 may be of wood, stone, or concrete and the abutment 18 can also be of wood, stone or concrete. The inner ends of the approaches 90 16 rest on the depressible beam 7 and the beam 7 is depressed when a vehicle moves on the approaches 16. The approaches 16 are duplicates. For automobiles or motor vehicles, the approaches may be constructed 95 as shown in Figs. 1 and 3 with curved blocks 19 attached to suitable beams. For animal propelled vehicles, the approaches would have to be made with complete floors. The doors or gates 5 and 6 can be or will be 100 closed by gravity when the vehicle moves off of the approaches. For making the closing certain or positive, springs 20 are attached to the depressible beam 7 and to the doors 5 and 6. If the doors are slow in 105 starting to close, the springs will act to start the doors. The springs 20 will also serve as cushioning means to prevent hammering of the parts. Provision is made for regulating the tension of the springs. The levers 110

8 must have the proper curvature to permit the required movement of the doors and to make the movement easily accomplished. The gates and the doors are operated in the same manner. The doors 21 to the garage 22 shown in Fig. 2 are operated in the same manner as the gates shown in Fig. 1.

For adjusting the gate or door in case of sagging or other cause, provision is made for 10 adjusting the door or gate. The upright 2 has a horizontal slot 23 is made for movement of the bolt 4. The bolt 4 is held at different points of adjustment by a thumb screw 24. The pressure of the gate or door 15 against the fulcrum bolt 4 will keep this bolt pressed against the screw 24. The adjustment of the fulcrum bolt will keep the doors in alinement.

The approach 16 for the inside of the 20 garage 2 need not be as long as the approach outside of the door. The abutment 18 should be on a level with the ground. The approaches 16 are held against displacement toward the gates or doors by open hinges 25 which catch over the beams 17 and are attached to the undersides of the ends of the beams of the approaches 16. The abutments 18 prevent outward displacement of the approaches 16.

30 What I claim, is,—

1. An automatically operated gate comprising fixed uprights on each side of the passage-way, a pair of swinging gate members provided with fulcrum bolts supported 35 in said uprights, a depressible bar, link bars pivotally connected to said depressible bar and provided with roller bearings at their upper ends, curved levers attached to said gate members and engaged by said link bars 40 through said roller bearings, and approaches to said gate members pivotally supported at

their outer ends resting on said depressible bar and adapted to press said bar downwardly for opening said gate members.

2. An automatically operated gate comprising 45 fixed uprights on each side of the passage-way, a pair of vertically swinging gate members provided with fulcrum bolts supported in said uprights, curved operating levers fixedly attached to said gate members, a depressible bar operating between members of said uprights, link bars pivotally connected to said depressible bar and provided with roller bearings at their upper ends engaging said curved levers, and approaches 50 pivotally supported at their outer ends and resting loosely on said depressible bar and adapted to press said bar downwardly and open said gate members when weight comes 55 on the approaches.

3. An automatically operated gate comprising 60 pairs of uprights on each side of the passage-way, a pair of vertically swinging gate members provided with fulcrum bolts supported in said uprights and adapted to 65 swing between the members of said uprights, outwardly curved levers fixedly attached to said gate members, a depressible bar extending entirely across the passage-way, adjustable link bars pivotally connected to said depressible bar and provided with roller bearings at their upper ends engaging said levers, springs attached to said gate members and to said depressible bar, and approaches 70 pivotally mounted at their outer ends and resting loosely on said depressible bar and adapted to press said bar downwardly for opening said gate members.

In testimony whereof, I set my hand, this 5th day of April, A. D., 1921.

GEORGE W. BROWN.
